ADJUSTABLE CYLINDER HONE

Fred M. Kern and Kirke W. Connor, Detroit,
Mich., assignors to Micromatic Hone Corpora-
tion, a corporation of Michigan

Application May 15, 1931, Serial No. 537,576

7 Claims. (Cl. 51—184.4)

This invention relates to hones and particularly to a hone of the rotatable type which is employed for finishing the inner surface of cylindrical members such as cylinders for internal combustion engines.

Hones of the above mentioned type have been employed heretofore which were expandable a predetermined amount for the purpose of adjusting the diameter of the honing elements relative to the diameter of the cylinder to be honed. The honing elements could be expanded only a small amount and it required several sizes of adapters to have the honing tool cover the complete range of cylinder diameters employed on passenger automobiles to be found in the present day art.

This invention includes the provision of a honing tool which is constructed in such manner as to enable the honing elements to be expanded and contracted such an amount as to cover the complete range of cylinder diameters employed in present day passenger automobiles.

This degree of expansion is effected by providing element supporting members with arms which project beyond the center line of the tool. One side of each of the arms is provided with lands and grooves positioned at an angle for engaging similar lands and grooves provided on a centrally disposed, longitudinally movable actuating member. The longitudinal movement of the actuating member causes the respective lands and grooves to slide relative to each other to effect the inward or outward movement, as the case may be, of the honing element. The arms are of such length as to extend the maximum distance and just come within the radius of the honing elements when they are contracted to effect a minimum diameter.

The actuating member is of square shape, having lands and grooves disposed on all four of its sides for engaging the arms of four element supporting members. The longitudinal movement of the actuating member is effected by an internally threaded knob which operates on a threaded end of the member. The thread is of small pitch to require a maximum amount of rotation of the knob to provide a small movement of the actuating member longitudinally and also the movement of the element supporting members laterally.

The element supporting members are provided with spring clamping means for engaging the elements which are insertable in a channel like member thereof. The spring elements has a protruding end which is biased upwardly over one of the flanges of the channel like member to

engage a side of the element. The central portion of the element has an inwardly extending portion which registers with an aperture in the supporting web which prevents the longitudinal movement of the element relative to the supporting member. 5

A pair of trunnions is provided on the central body portion of the honing tool which are engageable by the end of a universally jointed member which extends above the honing tool and is provided with a tool engaging end portion which is engageable by a motor actuated tool driving device well known in the art, for the purpose of rapidly rotating the hone. The honing tool has two oppositely disposed honing elements provided with arcuate engaging surfaces and with two oppositely disposed members made of cork disposed midway between the honing elements and provided with arcuate surfaces for engaging and wiping the sides of the cylinder to be honed. 20 The cork members also aid in centering the hone in the cylinder and in supporting the honing tool in the cylinder when the operating mechanism is detached therefrom.

Accordingly, one object of the invention is to provide a hone of the above mentioned type which is expandable over a range which is sufficient to engage the walls of the cylinders of all passenger automobiles employed today.

Another object of the invention is to provide a honing tool of the above mentioned type with an actuating member which shall effect a lateral movement to the honing element when moved longitudinally by a threaded knob which engages a threaded end thereof. 35

A further object of the invention is to provide a honing tool of the above mentioned type with an element supporting member having a central aperture and an adjacent spring latching member which releasably retains the honing and wiping elements on the channel member thereof.

A still further object of the invention is to provide a honing tool of the above mentioned type with a plurality of trunnions and with a trunnion engaging element having universal movement which enables the hone to be actuated when the actuating rod is positioned at an angle and which permits the separation of the actuating member from the hone to permit the measurement of the cylindrical diameter without the necessity of removing and readjusting the honing tool. 45

A still further object of the invention is to provide members made of cork on the arms positioned between the honing element supporting 55

arms for frictionally engaging the sides of a cylinder and supporting the honing tool when disconnected from the actuating device.

Other objects and features of novelty of the invention will either be specifically pointed out, or will become apparent when referring, for a better understanding thereof, to the following description in connection with the accompanying drawing, wherein—

10 Figure 1 is an elevational view of a honing tool embodying features of the invention.

Fig. 2 is a sectional view of the structure shown in Fig. 1 taken on the line 2—2 thereof.

15 Fig. 3 is a broken sectional view of the structure shown in Fig. 2 taken on the line 3—3 thereof.

Fig. 4 is a sectional view of the structure shown in Fig. 3 taken on the line 4—4 thereof.

20 Fig. 5 is a sectional view of the structure shown in Fig. 3 taken on the line 5—5 thereof.

Fig. 6 is a sectional view of the structure shown in Fig. 3 taken on the line 6—6 thereof.

Fig. 7 is a view in elevation of an adjusting washer employed with the honing tool, and

25 Fig. 8 is a reduced broken view, in elevation, of a honing tool and operating mechanism mounted in a cylinder.

The invention comprises in general a central frame member 11 having a square central opening 12 in which an actuating member 13 is slideable longitudinally when an operating knob 14 is rotated for the purpose of moving the supporting members 15 laterally of the frame member 11.

The frame member 11 is provided with a plurality of cylindrical apertures 16 which communicate with and are tangentially disposed to the central opening 12 of the frame member. The upper portion of the frame is provided with a shouldered recess 17 in which the operating knob 14 is retained against longitudinal movement by the projections 18 on the end of the threaded trunnions 19 which engage a slot 21 on the lower periphery of the knob. Ball bearings 22 are provided between the shoulder of the recess 17 and the bottom surface of the knob 14 for the purpose of eliminating friction between the two surfaces when the knob is rotated.

The actuating member 13 is threaded on its upper end with a thread 23 of relatively fine pitch, which is engageable by a thread 24 provided in the central opening of the knob 14. The rotation of the knob 14, relative to the frame member 11, effects the longitudinal movement of the actuating member 13 in either direction, depending upon the direction of rotation of the knob. A plurality of serrations 25 are provided on the upper surface of the member 11 with which a pin 26, slidably retained in the knob 14, engages when biased thereagainst by a spring 27. A cap 28 encloses the end of the knob 14 and a knurled surface 29 is provided on the side of the knob to provide a finger hold when the knob is to be rotated. The pin 26 indexes the movement of the knob relative to the frame member 11 and retains the knob in predetermined position relative to the member after the adjustment of the knob has been accomplished.

The four sides of the square actuating member 13 are provided with lands 31 and grooves 32 positioned in angular relation relative to the longitudinal dimensions of the actuating member and slope in opposite directions on opposite surfaces thereof. That is to say, the lands and grooves on one side of the actuating member slope 75 to the right, while the lands and grooves on the

opposite side of the member slope to the left, the purpose of which will be explained hereinafter.

The elements supporting member 15 are four in number and are each provided with an element 33 of channel shape having two cylindrical arms 34 extending from the web portion thereof in an opposite direction to the flanges of the channel shaped portion. The arms are spaced from each other and register with apertures 16 in the frame member, with the arms on two of the channel members disposed a greater distance apart than the arms on the other two channel members, for the purpose of permitting the arms to cross each other when mounted in the frame member, as illustrated in Fig. 3.

10 The inner surface of the arms 34 are provided with lands 35 which are angularly disposed and are of such slope as to register with the grooves 32 and the lands 31, respectively, of the actuating member 13. The mounting of the arms 34 tangentially to and in engagement with the sides of the actuating member 13, position the honing elements in advance of the center line through the honing tool, to effect a maximum 15 amount of erosion of the engaging surface of the cylinder wall for a predetermined amount of pressure.

When the actuating member 13 is moved longitudinally, the sliding of the lands thereof in the respective grooves of the arm 34 causes a lateral movement of the supporting members 15 toward and away from the frame member 11, controlled by the direction of movement of the actuating member 13. As mentioned hereinabove, the lands and grooves are oppositely disposed angularly on opposite sides of the actuating member and are positioned in this manner for the purpose of effecting an opposite movement to the element supporting members 15, which project in opposite 40 directions from the frame member 11. The arms 34, on the elements supporting members 15, retain them axially aligned with the actuating member 13 and the elements, which are supported thereby, are retained in longitudinal parallel 45 relation to each other.

The honing elements comprise an abrading element 36 which is rigidly attached to a channel shaped member 37 of such over all width as to be receivable within the confines of the flanges 50 of the channel shaped portion of the supporting member 15. In Fig. 3, we have illustrated the flange member 37 as being provided with a rearwardly extending projection 38 which registers with an aperture 39 provided in the element supporting member 15 for the purpose of preventing the relative longitudinal movement between the members.

A latching member 41 is constructed from flat spring steel and is riveted or otherwise attached 60 to the central portion of the element supporting member 15 and is bent backwardly upon itself at 42 and flanged inwardly at 43 to extend over the flanges of the channel shaped member 33 and 37. The engagement of the flange 43 with the flange of the channel member 37 retains the channel member and therefore the abrading element 36 in fixed relation to the element supporting member 15. This construction effects the firm retention of the honing element in the element 70 supporting member 15 of the honing tool, which element is readily removable therefrom by pressing against the portion 42 of the latching member for causing the flange 43 thereof to be withdrawn from engagement with the flange of the 75

channel member 37, to permit the channel member and the associated abrading member 36 to be removed from the honing tool.

Referring to Fig. 2 it will be noted that two of the oppositely disposed supporting members 15 are employed for receiving and supporting abrading elements 36 for the purpose of effecting the honing of a cylinder. Diametrically disposed to each other and positioned between the abrading members 36 two wiping elements 45 are employed, which are supported in channel members 37 in the same manner as the abrading members 36 are retained therein. Various materials may be employed for constructing the wiping elements such as felt, wood, leather or the like, and it has been found from experiments that cork effects the most desirable result and is therefore a preferred material to be employed for constructing the wiping element.

The cork has considerable resiliency and the proper and uniform wearing properties which permit the honing elements to engage the cylinder wall with a predetermined pressure during the time the pressure of the wiping elements is sufficient to retain the honing tool within the cylinder when disconnected from its driving and supporting member. The engaging surfaces of the wiping elements 45 are of arcuate shape similar to the arcuate shape provided on the abrading members 36 which effect smooth engaging areas in contact with the cylinder wall.

Experiments have disclosed that two of the honing elements are sufficient to finish the cylindrical grinding operation within a reasonable time and that the provision of the cork material 45 between the honing elements not only guides and supports the honing tool in parallel relation to the cylindrical surface, but also cleans and wipes the surface in such manner as to effect a much higher polish and finish to the surface. A further advantage of the cork material resides in its inherent ability to wear proportionally to the amount of pressure applied thereto and to, therefore, wear in proportion to the amount the honing elements are worn away during the honing operation.

While the pitch of the threads of the actuating member 13 may be such as to move the element supporting members laterally, the complete range of movement we preferably employ a larger pitch in order that the lateral movement of the supporting member is less than the movement of the longitudinal actuating member. When this relation obtains, a finer adjustment of the honing and wiping elements ensues when the knob 14 is adjusted. To expand the elements over the complete range of movement when the greater pitch of thread is employed, it is necessary to reset the threads in the arms with those of the actuating member.

Slots 53 are provided at the top of each of the threads which register with the recesses 16 in the frame 11 when the actuating member 13 is moved downwardly. In this position the arms 34 are released from engagement with the actuating member and may be moved laterally in the recesses. In Fig. 7 we have illustrated a washer 54 having a central hole 55 which permits the washer to be positioned over the cylindrical end 56 of the frame 11. The overall dimension of the washer is such that, when the element receiving members 18 are pushed inwardly toward the frame into engagement with the washer, the upward movement of the actuating member 13 causes the engagement of the threads 31 with the next suc-

ceeding thread 35 of the arms and the complete longitudinal movement of the member actuates the elements 36 and 45 through the same expandable distance from a greater initial diameter. Further extension is possible through the employment of a washer 54 having a greater overall diameter to cause the teeth of the actuating member to initially engage the third tooth of the arms. The adjustment is limited by the length of the arms 34, being of such length as to extend within 10 the minimum diameter of the honing elements when the tool is in retracted position.

The trunnions 19, provided on the upper end of the frame 11 are engageable by an actuating member 47, as illustrated in Fig. 8. The actuating member 47 is of the bayonet type, being provided with a collar 48, having slots therein which register with the trunnions 19. The collar is pivotally mounted on a bifurcated extension of the operating shaft 49 to thereby effect a universally 20 movable connection therewith. The upper end of the shaft 49 is provided with a hexagon shaped extension 50 which may be engaged by a suitable tool driving mechanism 51 for the purpose of rapidly rotating our honing tool within the cylinder.

The employment of a removable actuating member is advantageous in that the cylinder may be measured without the necessity of removing the hone therefrom. The honing tool may be 30 pushed toward the bottom of the cylinder and the actuating member removed to permit access to the upper portion of the cylindrical surface to measure its diameter. The adjustment of the tool may be made without the necessity of 35 removing the actuating mechanism therefrom, as the knob 14 is readily accessible through the universal joint of the connecting end of the shaft which enables the tool to be operated when the 40 shaft is tilted at an angle.

While we have specified that the preferred embodiment of our invention utilizes a square longitudinally movable member, it is to be understood that it is within the purview of our invention to 45 provide a cylindrical member which is keyed against rotation and provided with one or a plurality of threads of large pitch for engaging and actuating the arms 34.

While we have described and illustrated but a single embodiment of our invention, it will be apparent to those skilled in the art that various changes, omissions, additions and substitutions may be made therein without departing from the spirit and scope of our invention, as set forth in 55 the accompanying claims.

We claim:—

1. In a honing tool provided with a frame in which a member is movable longitudinally for effecting a lateral movement to the honing elements, an adjusting member for moving the longitudinally movable member, cooperating with a threaded end thereof, means for retaining the adjusting member on the frame of the honing element which comprises a pair of members threaded 65 in the central portion and shouldered on an inner and outer portion, the inner shoulders engaging a slot in the adjusting member, the outer shoulders being employed for receiving an actuating member for said tool. 70

2. The combination with a receiving member for a honing element of a rotatable honing tool, of a strengthening and supporting member on the rear portion of said honing element having a projection on the bottom web thereof and flanges on 75

its sides, the said receiving member being provided with an aperture in which said projection registers to prevent the longitudinal movement of the members, and a latch on said receiving member for preventing the lateral movement of the element.

3. A latch for a honing element comprising a length of spring steel which is bent upon itself in such manner that one end constitutes a support for said latch while the other end extends over a portion of said honing element to retain it in latched position.

4. A tool provided with abrading and wiping elements having means for adjusting said elements laterally, the said wiping elements being made of cork.

5. A wiping element for a honing tool disposed between the abrading elements thereof, and ad-

justable laterally therewith, the said wiping elements being made of cork.

6. A tool for honing the wall of a cylinder, having at least one abrading element, and at least one additional element engageable with the cylinder and made of cork.

7. The combination with a receiving member for a honing element of a rotatable honing tool, of a strengthening and supporting member on the rear portion of said honing element having a projection, the said receiving member being provided with an aperture in which said projection registers to prevent the longitudinal movement of said element relative to said receiving member, and a latch on said receiving member for preventing the lateral movement of the element.
